POT CLEANER

Vincenzo James Gentile, Hartford, Conn.

Application November 12, 1946, Serial No. 709,223

2 Claims. (Cl. 15—164)

1

My invention relates to kitchen utensils and more particularly to a cleaner for pots, pans and the like.

The object of my invention is to provide a cleaner for pots and the like consisting in a metal brush equipped with a handle to prevent the hands of the operator coming in touch with the pots or pans, or the grease adhering thereto or with the soapy water, etc.

Another object of my invention is to provide a cleaner of the character indicated above, the handle whereof is adapted to be adjusted to any desired angle to facilitate the cleaning of corners, curves and the like portions of pots, pans and the like, which are usually difficult to be cleaned.

Other objects of my invention may appear in the following specification describing my invention with reference to the accompanying drawings illustrating a preferred embodiment of my invention.

It is however to be understood, that my invention is not to be limited or restricted to the exact construction and combination of parts described in the specification and shown in the drawings but that such changes and modifications can be made, which fall within the scope of the claims appended hereto.

In the drawings

Figure 1 is a perspective view of a pot cleaner according to my invention.

Figure 2 is a top plan view of the cleaner shown in Figure 1.

Referring now in detail to the pot cleaner forming the subject matter of my invention, the cleaner has brush member 10 consisting of a substantially rectangular back 11, in which a plurality of tufts of metal bristles 12 are imbedded. The back 11 may be made from wood, non-rusting metal or any other suitable and preferred material, and the bristles can be made from thin stainless steel or brass wire or any other suitable metal wire.

A U-shaped frame 13 is made from stainless steel or any other non-rusting suitable material and is secured to the end surfaces of the back 11 of the brush member 10, by means of countersunk screws 14 or the like, extending through the flanges 15 of the U-shaped frame 13. These flanges 15 extend rearwardly beyond the back 11 of the brush member 10.

A handle 16 is formed from a flat bar of stainless steel or the like by bending this bar centrally of its length into a loop 17. The bar portions 18 located forwardly of the loop 17 extend straight forwardly and parallel to each other and are secured in abutting position to each other by a rivet 19 or the like.

Then the two bar portions are curved outwardly

2

and forwardly, as shown at 20, and the foremost portions 21 of the handle 16 extend straight forwardly and parallel to each and are secured pivotally by means of rivets 22 to the portions of the flanges 15 of the U-shaped frame 13 extending beyond the brush back 11.

The above description shows clearly, that the brush member 10 and the handle 16 are adapted to be adjusted relative to each other, so as to obtain the most advantageous angle for cleaning corners, curves and the like in pots or pans or the like. The handle can be arranged, so that the hand wielding the cleaner does not come in contact with pot or pan to be cleaned, or with any grease or the like adhering thereto or with the fluid used for cleaning. The character of the bristle material combines the brushing effect with a scrubbing effect, assuring a thorough cleaning of the article treated with cleaner described above.

Having described my invention, I claim as new and desire to secure by Letters Patent:

1. In a cleaner for pots, pans and the like, comprising a brush back having a plurality of tufts of bristles projecting therefrom, a U-shaped member having the limbs thereof attached to the ends of the brush back and a handle connected to said limbs, the features which include having the intermediate yoke portion of the U-shaped member projecting forwardly of and spaced from the brush back and said limbs extending rearwardly of said brush back to terminate in rearwardly-projecting ends, and having the handle connected to the latter ends rearwardly of said brush back.

2. A cleaner for pots, pans and the like, including a brush back having a plurality of tufts of bristles projecting therefrom, a U-shaped member partly enveloping the brush back with the yoke portion thereof projecting forwardly of the latter and spaced therefrom and the limbs thereof attached to the ends of the brush back and terminating rearwardly of the latter in two rearwardly-projecting ends, and a handle attached to said rearwardly-projecting ends rearwardly of said brush back.

VINCENZO JAMES GENTILE.
